MEDICAL PRACTICE CHAIR

Norman E. Lauterbach, Newark, N. Y., assignor
to Ritter Company, Inc., Rochester, N. Y., a
corporation of Delaware

Application July 2, 1946, Serial No. 680,983

10 Claims. (Cl. 155—28)

1

This invention relates to chairs of the variety adapted for use by the medical profession during examinations, treatments, and minor operations, one object of the invention being to provide an improved chair of such character having a more adjustable, convenient, and efficient construction.

Another object is to provide a chair of the above character having head, back, arm, and foot rests adjustable to and from positions lying substantially in the plane of the chair seat, for converting the chair into a substantially flat, table-like support.

Another object is to provide such a chair having a compensated, anatomically correct hinge movement of the back and head rest sections relative to the seat, as required for the comfort of the patient.

Another object is to supply a chair of the nature described having connections, such as arm rest structures, between the back rest and foot rest sections for adjusting the foot rest section by the adjustment of the back rest.

Another object is to afford a chair having a construction such as described above in which leg and foot rest sections are releasably connected with a back rest section for movement with or independently of the latter.

Another object is to provide a chair of the character described in which the foot rest section is maintained in a horizontal position throughout its angular range of adjustment relative to the chair seat, as well as provisions for locating the foot rest at different levels to suit different patients in kneeling on the foot rests for certain examination work.

Another object is the provision of a leg rest pad adapted to support the patient's legs when the chair is adjusted to a horizontal position, to be used as a cover for the foot support when the latter is retracted to folded position and to be positioned on and used as a pad for the foot rest in the different elevated positions thereof.

Another object is the provision of a chair having a head rest adapted to be selectively positioned to afford either the usual head pads, or substantially flat rigid surfaces for supporting the head and neck of a patient against sagging during administration of an anaesthetic. A further and more specific object is to provide a head rest having means for automatically locking the flat head supporting surfaces in position for use.

A further object is to supply such a chair provided with stirrups for supporting the feet of a patient in suitable position for certain exam-

2

inations and so constructed as to be readily extended for use or compactly retracted to position at the sides of the chair.

5 A further object is to provide a chair having stirrups of the above character so supported as to be conveniently adjustable to different positions of use to suit different patients.

10 To these and other ends the invention resides in certain improvements and combinations of parts, all as will be hereinafter more fully described, the novel features being pointed out in the claims at the end of the specification.

In the drawings:

15 Fig. 1 is a side elevation of a chair embodying the present invention and arranged to support a patient in upright sitting position;

Fig. 2 is a front elevation thereof;

15 Fig. 3 is a rear elevation thereof;

Fig. 4 is a top plan view of the chair arranged horizontally with portions of the seat broken away to disclose parts of the mechanism;

20 Fig. 5 is a side elevation of the chair in the same general arrangement with parts of the seat broken away;

25 Fig. 6 is an enlarged fragmentary detail view of a latching means shown in Fig. 5;

Fig. 7 is a side elevation with the back rest and head rest lying substantially in the plane of the seat and with the leg rest so arranged that the patient may kneel on it;

30 Fig. 8 is a side elevation with the back rest and head rest in the plane of the seat, the foot rest being folded under the leg rest and the stirrups extended and elevated;

35 Fig. 9 is an enlarged top plan view of the seat frame and associated mechanism;

Fig. 10 is an enlarged fragmentary view of certain details of the mechanism shown in Fig. 9;

40 Fig. 11 is a fragmentary side elevation of the seat frame, partly broken away to show a locking means;

Fig. 12 is a sectional view on the line 12—12 in Fig. 11;

45 Fig. 12^a is a perspective view of the base portion on the back rest and of the means for locking it in position;

Fig. 13 is an enlarged sectional elevation of portions of the seat frame and back rest showing the back rest locking means;

50 Fig. 14 is a fragmentary view partly broken away and partly in section substantially as seen from the line 14—14 in Fig. 13;

Fig. 15 is an enlarged side elevation of the seat frame and the frame for supporting the leg and

55

foot rests and associated mechanism, partly broken away and partly in section;

Fig. 16 is an enlarged top plan view of the foot rest with the foot supporting section in raised position;

Fig. 17 is a front elevation of the same;

Fig. 18 is an enlarged side elevation of the head rest detached, with its flat surfaces in one head supporting position;

Fig. 19 is a rear view of the same with its flat surfaces in a different supporting position;

Fig. 20 is a top plan view of the head rest with its flat surfaces locked in supporting position;

Fig. 21 is a similar view with the head pads in supporting position;

Fig. 22 is an enlarged sectional elevation substantially on the line 22—22 in Fig. 21;

Fig. 23 is a sectional plan view substantially on the line 23—23 in Fig. 22;

Fig. 24 is a side elevation partly broken away and partly in section showing an arm rest and stirrup supporting means;

Fig. 25 is an enlarged sectional elevation on the line 25—25 in Fig. 24;

Fig. 26 is a front elevation of the parts shown in Fig. 24;

Fig. 27 is a side elevation of a stirrup and part of the supporting means therefor detached;

Fig. 28 is an enlarged side elevation, partly in section, showing the stirrup supporting means, and

Fig. 29 is an enlarged view, partly in section, of parts of the arm rest shown in Fig. 24.

The preferred embodiment of the invention herein disclosed, by way of illustration, comprises a chair having a circular base 40, Fig. 1, supporting an electric motor 41 and a housing 42 for hydraulic mechanism for raising and lowering a chair supporting column 43 which is mounted for rotation also in the housing, as well understood in the art. At 44 is a foot lever controlling the rotation of the chair and at 45 are foot levers for raising and lowering the chair. These parts for moving the chair column may have any known or suitable construction and form no part of the present invention.

The chair column carries at its top a generally circular supporting head 46 formed with bearings 47, Figs. 4 and 9, for trunnions 48 by which a seat frame 49 is supported for tilting movement on the chair base. Means are provided, as hereafter described, for releasably locking the seat frame in adjustably tilted position. The seat frame 49 is a generally rectangular, hollow frame, as shown, on which the back rest, arm rests, and leg and foot rests are supported in connected relation for movement together simultaneously to different adjusted positions. The back rest and its adjustable association with the seat frame will be first described.

The rear of the seat frame is formed with an integral, hollow, box-like portion indicated generally at 50, Figs. 9, and 11 to 13, inclusive, with which the back rest is pivotally connected. This portion 50 comprises spaced, rearwardly extending walls 51 the front and lower sides of which are curved substantially in a semi-circle, as shown. Walls 51 are formed with bearings for a spindle 52, Fig. 13, pivotally supporting an irregularly shaped member 53 forming the base portion of the back rest, and carrying means for locking the back rest in different pivotally adjusted positions, as hereafter described. Fixed on and extending upwardly from member 53 is a post 54, Fig. 1, slidably received in a bearing in a member 55

having in its rear face an undercut or dove-tail vertical groove (not shown) slidably receiving a similarly shaped tongue on a member 56. Member 56 is provided with a clamp (not shown) operated by a handle 57 for locking its tongue in vertically adjusted position in the groove of member 55. Member 56 is provided at its upper end with lugs 58 between which is pivotally supported a depending arm 59 secured to the rear side of a substantially rectangular, padded back rest 60 shaped to conform comfortably to the patient's back. Member 56 is also formed on its rear wall with an undercut or dove-tail vertical groove slidably receiving a tongue on a member 61 provided with clamping means (not shown) operated by a handle 62 for locking it in vertically adjusted position on member 56. Member 61 is the lower supporting part of a head rest constructed as hereafter described. Such back and head rest parts 56 to 62, inclusive, may have any known or suitable construction, being well understood in the art and forming no part of the present invention.

The means for locking the back rest in adjustably tilted relation to the chair seat frame 49 comprises a part 63 (Figs. 13 and 14) projecting downwardly from the base portion 53 of the back rest and having a wedging block 64 set into its lower edge and secured by a screw, as indicated at 65. Block 64 has its opposite ends tapered forwardly and inwardly as at 66 for cooperation with cylindrical rollers 67 rolling between the tapered ends of the block and hardened metal wear strips 68 of arcuate shape secured to the spaced walls 51 as by means of screws 69. Leaf springs 70 fixed to portion 63 of the back rest, as by means of screws 71, have their free ends bearing against the rollers 67, respectively, so as to normally press the same into wedging engagement between the ends of the block 64 and the wear strips 68, thus normally locking the back rest against rearward tilting movement. A bar 72 is secured at its ends, as by means of screws 73, to the flanges 51, respectively, and carries, intermediate its ends, a pair of lugs 74 positioned to be struck by the part 64 of the base of the back rest, so as to form stops limiting the downward tilting movement of the back rest assembly.

The means for releasing the back rest locking 50 means comprises an arm 75 extending rearwardly from base portion 53 of the back rest and recessed at 76 for the reception of the lower end 77 of a lever 78 extending upwardly in rear of the back rest so as to be in convenient reach of the operator. Lever 78 is pivotally supported on a spindle 79 journaled at its ends in the opposite walls formed by recess 76 in arm 75. The lower end 77 of the lever is extended laterally as at 80, Fig. 14, and formed with a slot 81 extending upwardly therein through its lower edge, for the reception of a plate-like member 82. Studs 83 are threadedly engaged in holes in the lateral extensions of the lever, so as to bear at their lower ends against the upper edge of plate 82, these studs being locked in adjusted position by means of nuts 84.

Plate 82 is received at its lower edge within an upwardly turned flange 85 in a housing or shell 86 having forwardly extending opposite 70 side walls 87 pivotally mounted on the back rest spindle 52. Each wall 87 has a forwardly extending arm 88, the end of which is reversely bent upon itself, as at 89, to provide a thickened terminal portion. These arms are positioned to extend between the wedge-shaped ends 66 of

bar 64 and the arcuate plates 68 on the seat frame, for engagement with the wedging rollers 67, and it is evident from this construction that forward movement of lever 78 presses downwardly on plate 82, so as to swing shell 86 counterclockwise, Fig. 13, and thus engage and free the rollers 67 to release the back for lowering adjustment.

To normally maintain the back rest locked in position for sustaining the weight of the patient, the lower end 77 of lever 78 has a finger 90, Fig. 13, arranged to bear downwardly on a downwardly extending pointed end 91 of a short lever 92 located in a slot in the end of lever 78 and pivoted on its spindle 79. This end of lever 92 is arranged to bear against a leaf spring 93 fixed by a screw 94 to the portion 63 of the back rest, these parts being so arranged that the spring normally presses the short lever 92 in a counterclockwise direction (Fig. 13), so as to maintain lever 78 in a rearward position from which it may be moved forwardly, as described above, to release the back rest locking or wedging means. The upper end 95 of the short lever 92 is so arranged that at the lower limit of its movement, with lever 78 released, it snaps behind a shoulder 96 formed on the bottom wall of the portion 50 of the seat frame, thus locking the back rest against raising movement also until the upper end of the lever 92 is lifted by pressing lever 78 toward the back rest. The back rest will thus be locked against movement in either direction when lowered to the position in which it lies substantially in the plane of the chair seat. It will be noted that the controlling lever 78 moves with and maintains a uniform relation to the rear side of the back rest, so as to be readily located and grasped by the operator and that only a slight pressure of the lever toward the back rest is required to release it for movement to the desired position. The above back rest locking means is claimed in my divisional patent application, Serial No. 119,093, filed October 1, 1949.

The tilting or pivotal movement of the back rest about the spindle 52 located in rear of the seat and of the back of the patient, is compensated by means for automatically sliding the associated back rest portions on post 54, toward the chair seat, as the back rest is lowered from the vertical position shown in Fig. 1. Such means preferably comprises an advantageous construction and association of the arm rests by which they effect such sliding movement of the back rest in relation to a second pivotal axis located intermediate the front and back of the seat.

To this end, each arm rest comprises a metal frame 97, Figs. 1, 24, and 25, on which is mounted an arm receiving portion 98 having a generally broad and substantially flat upper surface which may be made of plastic or other known material suitable for the purpose. The arm rest frame has its upper rear end 99 pivotally connected at 100 with arms 101 extending forwardly from the part 55 of the back rest which slides on the pivoted post 54. At its opposite end each arm rest has fixed thereto a trunnion 102 pivotally supported in a bearing in the side of the seat frame. The trunnion extends through beyond the face of the inner side of the frame for connection with mechanism hereafter described. Strong coiled springs 103 connected to the seat frame at 104 and to the arm rest trunnions, serve to counteract the weight of the patient against the back rest and to assist in lifting the back rest and patient to a sitting position.

It is evident from this construction that as the back rest is lowered pivotally about spindle 52, the arm rests slide the back rest downwardly on post 54 toward the seat, thus controlling its movements with reference also to the axis of the pivotal connection of the arm rests with the seat frame, intermediate the front and rear of the seat. Such movement of the back rest is thus controlled with reference to pivots located in rear 10 and in front of the back of the patient, so as to accomplish an anatomically correct compensating hinge movement of the back and head rest sections of the chair. Furthermore, the arrangement and connection of the arm rests is such that 15 while functioning efficiently in the upright position of the back rest, as shown in Fig. 1, they may be lowered with the back rest so as to lie substantially in the plane of the seat, as shown in Fig. 5, thus extending in lateral directions the 20 substantially flat, table-like support provided by the chair as a whole, and serving as arm supports throughout the entire angular range of adjustment of the chair.

As explained above, the seat frame is supported for tilting movement on the top 46 of the elevating column 43 and the arm rest structure is utilized in part for controlling means for locking the seat frame in adjustably tilted position on the column. Such means preferably comprises a sleeve 105 keyed on the inner end of the trunnion 102 of one of the arm rests (Fig. 10). Fixed in this sleeve are one or more radially extending pins 106 received in inclined slots 107 in a cap 108 rotatably and slidably mounted on the sleeve so as to be controlled for movement both concentrically and axially of the sleeve. The cap 108 has a strap 109 clamped thereto and forming part of the end of an angular lever 110, Figs. 9, 10, and 15, extending rearwardly and upwardly along the under 40 side of the adjacent arm rest. Set concentrically in the cap is a threaded plug 111 of hardened steel having therein a socket 112 for the reception of the rounded and hardened end 113 of a thrust element or rod 114. This end of the rod is thus 45 supported concentrically with the trunnion of the arm rest, so as to be undisturbed by its tilting movement on the seat frame, and it will be seen that the swinging of lever 110 rotates cap 108 whose inclined slots 107 move the cap axially of 50 the sleeve to press its plug 111 against rod 114 to thrust it longitudinally. It will also be noted that lever 110 is mounted on and follows the movements of the arm rests, so as to be conveniently and easily located for actuation by the operator 55 of the chair. Rod 114 thrusts at its opposite end against the resistance of spring actuated means for operating the locking means controlling the tilting movement of the seat frame on the elevated column of the chair base, as hereafter described.

60 Thrust rod 114 has its other end 115, Fig. 9, rounded and hardened and seated in a socket 116 in a lever 117 pivoted at 118 on a lug 119 on the head of the elevating column. The rod socket 116 is located concentrically with the axis of the seat frame trunnions 48, so that the rod is unaffected by tilting movement of the seat frame on the column. At 120 is a coiled compression spring having one end seated in a recess in lever 117 and the other end seated in a recess in an extended 65 portion 121 of the adjacent column bearing 47.

The means for releasably locking the seat frame in its adjustable tilted positions on the base comprises, preferably, a block 122 (Figs. 9, 11, and 12) pivotally supported by trunnions 123 having 70 bearings in lug 119 and a cooperating lug 124

spaced therefrom on the head of the column. This pivoted block 122 is formed with a bearing opening which slidably receives a spindle 125 connected with the chair frame, as hereafter described. Block 122 has a slot 126 extending inwardly to its bearing to provide for compressive clamping of the block around the spindle to lock it thereto. Such locking compression of the block is preferably accomplished by means of a rod 127 sliding longitudinally in a bore in lug 119, with one end bearing against lever 117 and the other against the adjacent side of the block. The opposite side of the block is supported by a short stop rod 128 fixed in lug 124.

Locking rod 125 is carried by a head 129 formed on or otherwise secured to the top of the rod and pivoted on a spindle 130 carried in lugs 131 projecting inwardly from an abutment 132 on the seat frame. A coiled compression spring 132a, carried by an adjusted screw 132b, on the rod head 129, in position to strike block 122, serves to cushion the return of the seat frame to horizontal position, and a washer 132c, on the lower end of the rod, limits its movement in the opposite direction.

It will be evident from this construction that the pressure of spring 120 against lever 117 normally thrusts rod 127 longitudinally to compress block 122 into locking engagement with the spindle carried by the seat frame so as to lock the latter in adjusted position. Lever 110 may be rotated through a slight angle, however, to cam cap 108 axially of sleeve 105, as previously explained, and thereby thrust rod 114 against lever 117 and thus release block 122 to relieve its locking action on the seat frame rod 125, thus freeing the seat frame for tilting movement as long as lever 110 is held in such position. During such tilting movement of the seat frame, the thrust rod 114 is turned bodily about its end 115 concentric with the tilting axis of the frame, so as not to affect the operation of the frame locking means, notwithstanding the location of the other end of the thrust rod in eccentric relation to such pivotal axis. The adjustable seat frame and locking means therefor are claimed in my divisional application, Serial No. 119,094, filed October 1, 1949.

The invention further comprises a frame pivotally connected with the front end of the seat frame for supporting adjustable leg and foot receiving rests, this frame being arranged for movement either conjointly with or independently of the back and arm rests, as may be found desirable. To this end a shaft 133, Figs. 9 and 15, is mounted for rocking movement at its opposite ends in bearings in the sides of the seat frame. Mounted to rock independently on the shaft is a sleeve 134 to the opposite ends of which are fixed a pair of spaced arms 135 having upper ends of "goose neck" shape to avoid interference with the front end of the seat frame. Arms 135 are rigidly connected with each other, as by means of a cross bar 136, Fig. 15, and form a hinged frame of rigid construction for supporting the leg and foot rests, as hereafter described. Arms 135 are formed with outwardly projecting shoulders 137 adapted to strike the bottoms of the sides of the seat frame and stop the foot rest frame in its lowermost position, as shown in Fig. 15. The means for pivotally elevating this frame by the pivotal lowering of the back rest of the chair will now be described.

Keyed to the ends of shaft 133, beyond the ends of sleeve 134, are a pair of cross arms 138

75

each having one end pivotally connected at 139 with a link 140 pivoted at its opposite end 141 to the outer end of an arm 142 keyed on the trunnions, 102, of the arm rests, so that the tilting movement of the back rest, imparted to the arm rests, as described above, is transmitted by the arm rests as a rocking movement of shaft 133, the arm rests serving in this arrangement as an actuating connection between the back rest and the foot rest frame.

The opposite or lower end of one arm 138 is pointed as at 143, Fig. 6, for engagement with the suitably shaped end 144 of a plunger 145 sliding longitudinally in a hole 146 in the adjacent arm 135 of the foot rest frame. Plunger 145 has its other end reduced in diameter to provide a chamber housing a coiled compression spring 147 tending to project the plunger into the path of movement of the actuating arm 138. Pivoted at 148 to the reduced end of the plunger is a lever 149 having opposing surfaces 150 and 151. Pivot 148 is located nearer the surface 150 so that when the lever is turned to present that surface to the frame, plunger 145 is released for movement by its spring into the path of the actuating arm 138. Lever 149 may be turned, however, to present its other surface 151 to the frame arm 135, thereby withdrawing the plunger into its bearing out of the path of the actuating arm 138, so as to disconnect the foot rest frame and leave it unaffected by tilting movement of the back and arm rests.

For supporting the foot rest, arms 135 are connected at their lower ends by a shaft 152, Figs. 15 to 17, inclusive, on which are pivotally carried a pair of spaced arms 153 extending rearwardly from the main supporting frame 154 of a sectional foot rest indicated generally at 155. Means are provided, comprising a parallel motion linkage, for controlling the pivotal movement of the foot rest on its frame, so as to maintain it substantially horizontal, or parallel with the chair seat, in any tilted position to which the foot rest frame may be moved with the back rest, as may be seen by comparison of Figs. 1 and 5.

For this purpose the foot rest frame 154 has spaced rearwardly extending arms 156 carrying a shaft, or trunnions 157, arranged to be engaged in open notches 158 in the lower ends of a pair of spaced links 159 pivoted at their upper ends on trunnions 160 on lugs 161 on the seat frame. For maintaining the links 159 in position for engagement with the foot rest, a metal strap 162 has its ends fixed to the rear side of a cover plate 163 having ears 164 fixed by screws to the arms 135. The intermediate portion of strap 162 is deflected to pass behind a rod 165 connecting the links 159 so as to hold the links in position for engaging the foot rest. Means are provided for releasably securing the links to the foot rest comprising a latch 166 pivoted at 167 to one of the links, and having a stop flange 168 at one end, and hooks 169 at the other for engagement with the shaft 157, to hold it in the end notches of links 159, the latches being urged to engaging position by a gravity arrangement or by springs, as desired. The ends of the latches beyond their hook portions are preferably so shaped, as at 158a, as to be cammed back to clear notches 158a, by the engagement therewith of shaft 157, so that the foot rest may be latched to the links 159 without manual operation of the latches. The latch may be manually operated to release the foot rest for folding pivotally upwardly against the frame, as hereafter referred to.

The foot rest 155 comprises the supporting frame 154, forming its lower section, and a flanged plate 170 forming its upper section. The lower section 154 comprises a supporting plate 171. Fig. 17, having upwardly turned marginal flanges 172 providing a compartment for receiving the upper section in its lowermost position. The upper section 170 comprises a plate 173, covered by a sheet of rubber or other suitable composition 174, for contact with the feet and has downwardly turned marginal flanges 175 adapted to fit within the flanges of the lower section. The upper section is adjustably supported on the lower section by means of inner and outer pairs of links 176 and 177 pivotally connected as at 178. The links of the inner pair are rigidly connected by cross bars 179, while the outer links are rigidly connected by cross bars 180. One end of each inner link is pivoted at 181 to the ends of an up-standing rib 182 on the lower section plate 171 and the opposite ends of the inner links and their connecting cross bar 179 have sliding contact with the under side of plate 173 of the upper section, being supported on a keeper bracket 179a and guided by engagement of a pin 179b in the cross bar with a slot in the keeper bracket, as shown. One end of each of the outer links 177 is pivotally connected at 183 to bracket arms 177a on the under side of plate 173 of the upper section. The cross bar 180 at the opposite ends of these links is formed with recesses 187 for engagement with detents provided by the hardened wear heads 188 and 189 of studs 190 and 191 fixed in inclined surfaces formed on the plate 171 of the lower section.

The upper section of the foot rest is provided with clips 192 and 193 located at opposite ends of its front side. By lifting upwardly on clip 192 to raise the upper section, its links 177 are swung pivotally to cause the connecting cross bar 180 to ride over the detents 188 and 189 until the upper section is adjusted to a desired elevation, after which the release of the lifting clip allows the cross bar to drop and engage at its recesses 187 with the desired detent and thus support the upper section. To lower the upper section, clip 193 is first slightly raised to shift the weight of the upper section toward the supporting links 177 at its opposite end, thus causing the bar connecting these links to rise above the detents 188 and 189 and so release the upper section for depression to a lower position, or in nested relation in the lower section.

The leg rest comprises a rectangular frame 195 (Figs. 7 and 15), surfaced by a cushioning pad 196 and having upwardly projecting lugs 197 fixed at opposite sides of its top. These lugs are pivotally connected with the ends of bars 198 slotted longitudinally as at 199 and having enlarged arcuate opposite ends 200. The slotted portions of the bars embrace studs 201 (Fig. 15), fixed to the side arms of the frame and the arcuate edges at the ends 200 of the bars are adapted to rotate in contact with concentrically curved ribs 202 on the side arms of the frame, except that such rotation may be restrained by engagement of shoulders 203 (Figs. 7 and 15) on the bar edges with the forward ends of the ribs. It is evident from this construction that with the arcuate bar ends and shoulders 203 so engaged with ribs 202, the bars are latched against movement on their studs and the leg rest is pivotally suspended in position against the front of the leg rest frame, so as to be out of the way in the upright position of the chair, shown in Fig. 1, or to support the legs of the

patient in the horizontal position of the chair, as shown in Fig. 5. Or, the leg rest may be first swung upwardly on its pivots and the foot rest released and folded upwardly and inwardly against the front of the frame and the leg rest then pivotally lowered to cover it, as shown in Fig. 8, in which position the leg rest serves also as a comfortable surface of contact when the operator assumes a position close to the front of the chair seat, as required in some examinations.

The leg rest may also be pressed upwardly to raise its bars 198 sufficiently to release their shoulders 203 from the ribs 202, after which the bars may be rotated and slid forwardly on their studs to allow the leg rest to be moved forwardly and downwardly and placed upon the foot rest in any elevation of the latter, as illustrated in Fig. 7, to form a comfortable kneeling surface for the patient. An additional pad 204 may be fixed at the top of the leg rest frame to supplement the pad 196. The foot and leg rests are thus provided with a wide variety of adjustments for adapting them to serve a variety of purposes. The foot rest retains a horizontal position throughout the range of angular adjustment of its frame on the chair seat, but it may be easily retracted against the frame when desired. When again extended to horizontal position, the foot rest will be engaged, regardless of the angular position of the frame on the seat, by the positive means for maintaining it horizontal or level. It also contains an extremely compact device for providing various levels for kneeling when the chair parts are arranged for rectal examination work. The adjustable leg and foot rest construction is claimed in my divisional application, Serial No. 119,095, filed October 1, 1949.

The head rest comprises, in addition to the slide 61, a swiveling head 205, Figs. 1, 18, and 19, supporting at its upper end the shank bar 206 of a yoke 207. The head 205 has a swiveling connection at opposite ends with the parts 61 and 206, respectively, and includes means operated by a handle 208, for clamping such parts in adjusted position. This swiveling head may have the construction, for example, disclosed in United States Letters Patent No. 1,817,755, to Adam J. May, and forms no part of the present invention.

Yoke 207 has threaded openings in its ends for the reception of threaded studs 209, Figs. 18 to 23, inclusive, locked in adjusted position by nuts 210. Studs 209, extending inwardly of the yoke have reduced portions 211 (Fig. 3) and terminate in enlarged heads 212 for the purpose hereafter described. Within the outer yoke 207 is an inner yoke 213 having openings in its ends for the reception of the inner ends of the studs 209 on which the inner yoke is pivoted. Each end of the inner yoke is formed with a bearing opening 214, Fig. 22, extending transversely of the studs 209, for the reception of opposed trunnions 215 carried by spaced arms 216 on head rest members 217. Trunnions 215 have portions rotatably fitted in opening 214 of the inner yoke, the outer ends of the trunnions being squared and fitting in square openings in arms 216 so that pivotal adjustment of the head rest members 217 is accomplished by turning the trunnions in their bearings 214 of the inner yoke. The trunnions are formed at their inner ends with eccentrics 218 positioned in the reduced portion 211 of stud 209 and adapted, on rotation, to bear

against head 212 of the stud, for clamping the parts in position, as hereafter described.

Each head rest member 217 comprises the usual cupped circular head pad 219 and also a substantially plane-shaped portion 220 having a substantially flat surface 221 for supporting the head of the patient in certain examinations hereafter referred to. It is evident from the above construction that the pads 219 of member 217 may be rotated to head supporting position, as shown in Fig. 21, during which movement the eccentrics 218 tend to press studs 209 outwardly while reacting inwardly upon the ends of the inner yoke, thus relieving any binding pressure on the pivotal parts of the inner yoke, and of head rest members 217. The pad portion of the head rest member is thus released for movement freely to position to accommodate the head of the patient. On the other hand, as each head rest member is swung to position its flat surface 221 in supporting position, as shown in Fig. 20, its stud eccentrics 218 bear inwardly on the inner head 212 of the stud 209, while reacting against the bearing in the end of the inner yoke, thereby drawing the ends of the inner and outer yokes into clamping engagement with each other end at the same time clamping the trunnions 215 of the head rest member 217, so that the latter and the inner yoke 213 are automatically clamped in position. The inner yoke may be adjusted at a desired angle to the outer yoke, before being clamped, and the flat head supporting surfaces 221 may be arranged to lie substantially in the plane of the back rest in the horizontal position of the latter, as shown in Fig. 5, in which these parts and the leg and foot rests form a substantially flat, table-like support. In this position the flat surfaces 221 furnish immovable supports on which the face, or the side or back of the patient's head may be rested during examination so as to prevent sagging of the patient's neck, as desirable during administration of anaesthetics. The above head rest construction is claimed in my divisional application, Serial No. 119,096, filed October 1, 1949.

The invention also provides, in combination with the above construction, an advantageous stirrup means located adjacent the seat frame for supporting a patient's heels while in a reclining position on the chair, as required in certain examinations. Such means is preferably supported in adjustable relation to the arm rests, for which purpose the arm rest frame has its upper side 222, Figs. 24, 25 and 29, hollowed out below the arm receiving upper surface 98, so as to form a chamber, or guideway, 223, slidably receiving an extensible stirrup arm hereafter described. Depending from the under side of the arm receiving portion 98 into guideway 223 are a pair of lugs 224 and 225, Fig. 29, formed with openings for the reception of set-screws 226 and 227 in the side 222 of the frame at the ends of the guideway and having tapered ends arranged to engage the lower sides of the openings, so as to fix the arm portion 98 on the upper side 222 of the arm rest frame. Each stirrup bar 228 passes loosely through a guide opening 229 in the arm rest frame at the forward end of the guideway and also through a similar opening in a wall 230 on the frame extending transversely of the guideway. This opening is reduced in size by a shim means 231 to loosely fit the bar 228. A leaf spring 232 is fixed on the arm portion 98 to bear at its free end against the stirrup bar 228 forwardly of its bearing on wall 230 so as to tilt

the forward end of the bar downwardly about its bearing in the wall 230. The under side of the bar is formed with a series of spaced recesses 233 for engagement with the head of a set-screw 234 in the bottom of the guideway at its forward end. By means of this construction, the stirrup bar 228 is normally secured against sliding in its guideway by the engagement of one of its recesses with the head of screw 234, but the upper end of the bar may be slightly lifted against the tension of spring 232, so as to clear the screw and permit the bar to be adjustably extended forwardly of the chair, in which position it may be again secured by engagement of one of its recesses with the screw head.

The stirrup bar 228 has its forward end 235 turned downwardly and outwardly and formed as a trunnion for pivotally supporting a short extension 236 having an oppositely inclined end 237 formed with a bearing mounted to swing on the trunnion 235. The trunnion has a peripheral slot 238 extending part way around it for receiving the projecting inner end of a screw 239 in the bearing of extension 236, so as to limit the swinging movement of the extension on the trunnion. The extension terminates in an angular arm 240 and carries a parallel motion linkage for supporting the stirrup, which will now be described.

30 An elongated housing 241 is pivoted at 242 on extension 236 and the extension arm 240 has pivoted thereto at 243 a link 244 sliding longitudinally in the housing. The opposite end of the housing is pivoted at 245 to a lug 246 on the stirrup 247 which is also pivoted at 248 to the forward end of link 244, thus creating a parallel motion linkage by means of which the housing may be tilted upwardly at its forward end to elevate the stirrup which is maintained in substantially horizontal position parallel with the chair seat by such linkage.

For securing the stirrup in its several positions of vertical adjustment, a latch bar 249 is pivoted to the housing at 245 and has at its opposite end a sharp corner 250 arranged to engage in a series 45 of notches 251 in link 244. A spring 252 is fixed at one end to link 244 and at its other end to the latch bar 250 to normally position the latter for engagement with one of the notches, to maintain the stirrup in an elevated position. To release the linkage for lowering the stirrup, a bar 253 is pivoted at 248 on link 244 and carries a button 254 projecting downwardly beyond the link, these parts being so arranged that upward pressure on the button raises this release bar to engage and raise latch bar 250, so as to clear the notches in the link and permit the lowering of housing 241 with its stirrup to horizontal position in which it is arrested by engagement of its top wall with the top of the arm extension 236. Fig. 8 illustrates the range of this vertical adjustability of the stirrup.

It is evident from the above construction that with the housing 241 and the stirrup 247 in the horizontal position shown in dotted lines in Fig. 8, these parts and the arm extension 236 may be swung on trunnion 235 to the position shown in Fig. 1, compactly folded out of the way outside and below the corresponding arm rest, in which position these parts, finished with chrome plating, form an attractive part of the chair. In use, with the chair parts in the upright position shown in Fig. 1, the stirrups are swung outwardly and forwardly about their inclined pivots 70 to a position in which they are inclined forwardly

and downwardly substantially in extension of the arm rests. In this position, the patient's heels may be located in the stirrup rings, after which the chair parts may be tilted to a reclining position which automatically brings the patient into a correct anatomical examining position. A top plan view of the parts in this position is shown in Fig. 4. The above foot supporting stirrup construction is claimed in my divisional application, Serial No. 119,097, filed October 1, 1949.

The invention supplies an improved and advantageous arrangement of back and arm rests relative to the seat frame which produces an anatomically correct compensating hinge movement of the back and head rests, thus properly accommodating the movements of the back and head rests to the movements of the patient's body and so contributing materially to the patient's comfort. Such movement of the back and head rests are conveniently controlled by a locking lever uniformly positioned in rear of the back rest, so that these parts may be easily tilted to lie substantially in the plane of the chair seat, with spring means for counterbalancing the weight of the patient and chair parts during such movement. The broad surfaced arm rests are associated with the back rest and seat so as to be automatically tiltable with the back rest to lie in substantially the same horizontal plane, as a part of the table-like support so produced. The arm rests have the further function of serving as a linkage for automatically swinging the foot rest frame upwardly as the back rest is lowered, to raise the leg and foot rests to lie substantially in the same plane and thus convert the chair into an essentially flat, table-like support for the patient. The foot rest is maintained horizontal during such tilting movement and may be adjusted vertically, with or without the leg rest as a cushion, or folded compactly against the frame under the leg rest, as need may require. If desired, however, the leg and foot rest frame may be disconnected to remain in lowered position during movement of the other parts to a reclining position. The back rest is provided with a head rest having alternately available head supporting surfaces adapted, respectively, for either upright or reclining positions of the patient. The stirrup means are conveniently arranged for movement with the arm and back rest to facilitate adaptation to the movements of the patient and may be compactly folded back to an out of the way position. The chair, as a whole, may be conveniently tilted on its supporting column to a desired inclination to the horizontal, independently of the positioning of the several parts relative to the seat frame, and such tilting adjustment is conveniently controlled by means of a lever which is maintained in a given relation to one of the arm rests of the chair.

It will thus be seen that the invention accomplishes its objects and while it has been herein disclosed by reference to the details of preferred embodiments, it is to be understood that such disclosure is intended in an illustrative, rather than a limiting sense, as it is contemplated that various modifications in the construction and arrangement of the parts will readily occur to those skilled in the art, within the spirit of the invention and the scope of the appended claims.

I claim:

1. A chair comprising a seat frame, a back rest, means supporting said back rest for tilting movement on said frame, means supporting said back

rest for sliding movement toward and from said frame, and arm rests movably connected with said frame and with said back rest for effecting sliding movement of said back rest toward and from said frame during said tilting movement thereof.

2. A chair comprising a seat frame, a back rest, means supporting said back rest for pivotal movement about a pivotal point on said frame, means supporting said back rest for movement toward and from said pivotal point on said frame, and arm rests pivotally connected with said frame and also with said back rest for moving said back rest toward and from said frame and for movement by said back rest to position substantially in the plane of said seat, for converting said chair into a table-like support.

3. A chair comprising a seat frame, a guide member pivotally connected with said frame, a back rest slideable on said member, and arm rests pivotally connected with said frame and said back rest to effect said sliding movement of said back rest and to move said arm rests toward and from the plane of said seat during the pivotal movement of said back rest relative to said frame.

4. A chair comprising a seat frame, a guide member pivoted on said frame in rear of said seat, a back rest sliding on said member and having a pivotal movement therewith relative to said frame, and arm rests pivotally connected with said back rest and with said frame medially of said seat, for sliding said back rest on said member during pivotal movement of said member and said back rest relative to said frame.

5. A chair comprising a seat frame, a guide member pivoted on said frame in rear of said seat, a back rest sliding on said member and having a pivotal movement therewith relative to said frame, arm rests, means pivotally connecting said arm rests with said back rest and with said frame medially of said seat, for sliding said back rest on said member during pivotal movement of said member and said back rest relative to said frame.

6. A chair comprising a seat frame, a guide member pivoted on said frame in rear of said seat, a back rest sliding on said member and having a pivotal movement therewith relative to said frame, a foot rest pivoted on said frame, arm rests, means pivotally connecting said arm rest with said back rest and with said frame medially of said seat, and actuating connections between said arm rests and foot rest, for moving all of said rests simultaneously to positions lying substantially in the plane of said seat, for converting said chair into a table-like support.

7. A chair comprising a seat frame, a back rest having a tilting movement on said frame, a rock shaft on said frame, a connection between said shaft and said back rest for rocking said shaft by the tilting movement of said back rest, a sleeve having a rocking movement on said shaft, a foot rest frame fixed to said sleeve, an arm fixed to said shaft, a plunger on said foot rest frame for engagement with said arm, and means for moving said plunger to and from arm engaging position for releasably connecting said foot rest frame and back rest.

8. A chair comprising a seat frame, a back rest having a tilting movement on said frame, a foot rest frame having a tilting movement on said

9. A chair comprising a base, a seat frame on said base, a back rest pivoted to said frame, a leg rest, pivoted to said seat frame, and arm rest, means movably connecting said arm rest to said seat frame and to said back rest, link means connecting said arm rest to said leg rest for moving all of said rests simultaneously to a horizontal position substantially in the plane of said seat frame, in a predetermined position of elevation of said seat frame, for converting said chair into a table-like support, and spring means interposed between said seat frame and rests for counter-balancing the weight of said rests and of an occupant of the chair while said seat frame is maintained at said predetermined elevation.

10. A chair comprising a base, a seat frame on said base, a back rest pivoted to said frame, a back rest pad slidably mounted on said back rest, a leg rest pivoted to said frame, an arm rest pivotally connected to said frame and to said back rest pad, link means connecting said arm rest to said leg rest, for moving all of said rests simultaneously to a horizontal position and sliding said back rest pad toward said seat frame, in a predetermined position of elevation of said frame, and spring means interposed between said frame

and said rests for counterbalancing the weight of said rests and an occupant of the chair while said frame is maintained at said predetermined elevation.
